CONTROL MECHANISM

Philip L. DeJarlais and Hazen C. Pratt, Champlin, Minn., assignors to Hoffman Engineering Corporation, Anoka, Minn., a corporation of Minnesota

Application January 19, 1950, Serial No. 139,521

10 Claims. (Cl. 74—593)

1

This invention relates to control mechanisms and more particularly to a mechanism which can be inserted into a pull type control for disabling the action of said control at selected intervals under control of an electric circuit. In many mechanisms, such as punch presses, shears, forming presses and the like, the actuation of the press mechanism or other mechanism is controlled by means of either a foot treadle or hand lever or some other mechanical linkage which operates through a pull link for the actuation of clutch or power control, so as to initiate or stop actuation of the press or mechanism. In applying safety controls to such presses and the like, it has been found that disabling of the control, so as to stop the operation of the press or machine under selected conditions can best be accomplished by inserting in one of the pull links of the controlling system a device which in effect disconnects the link so that actuation of the treadle or lever does not impose upon the machine a force suitable for causing actuation. A machine control of this type is disclosed in the prior application of Charles L. Horn and Philip DeJarlais Serial No. 77,088 filed February 18, 1949, for Automatic Safety Guard for Power Presses. In said application actuation of the press is accomplished by means of a foot treadle, which pulls on the clutch control rod of the press so as to actuate the press. Safety controls are interposed utilizing a device which in effect disconnects the clutch control rod under certain conditions so that when the foot treadle is actuated the rod no longer exerts a pull on the clutch device of the machine and hence the machine does not actuate. This safety device is shown at 85 in Figure 3 of said application.

It is an object of the present invention to provide an improved releasing device which is positive in its operation, sturdy, easily manufactured and capable of repeated operation without malfunctioning.

It is a further object of the invention to provide an improved release mechanism for a machine control.

It is another object of the invention to provide a magnetically operated release mechanism for a control for disabling said control when the magnetic mechanism is de-energized.

It is another object of the invention to provide a releasable pull rod control utilizing a toggle joint capable of being held in straight condition by a magnetic mechanism.

Other and further objects of the invention are those inherent in the apparatus herein illustrated, described and claimed.

2

The invention is illustrated with reference to the drawings in which corresponding numerals refer to the same parts and in which

5 Figure 1 is a longitudinal sectional view, partly broken away, illustrating the apparatus of the instant invention;

10 Figure 2 is a transverse longitudinal sectional view taken along the line and in the direction of arrows 2—2 of Figure 1, it being noted that the sectional view of Figure 1 is taken along the line and in the direction of arrows 1—1 of Figure 2;

15 Figure 3 is a transverse longitudinal sectional view taken in the opposite direction as compared to Figure 2, and along the line and in the direction of arrows 3—3 of Figure 1;

20 Figure 4 is a side elevational view and illustrates a somewhat modified form of the invention.

25 Referring to the drawings, Figures 1, 2 and 3, which show an illustrative form of the invention, at 10 and 11 there is shown a pull rod which in the normal machine, such as a punch press or other mechanism, is a solid rod in which the parts 10 and 11 are the same piece of metal. This rod,

30 which may, for example, be a clutch control rod operated by a treadle at 13, is usually provided with a clevis at 14 that is adjustable by means of the screw-thread 15 and nuts 16 and 17 so as to adjust the length of the pull rod. Where safety controls are installed on such a press or other mechanism utilizing such a pull rod control, the safety controls serve to disable the pull rods and in effect serve to disconnect the portion 10 from the portion 11, so far as transmitting any pull is concerned, when the safety controls are actuated.

35 In the instant invention, one form of which is illustrated in Figures 1-3, the portion 10 of the rod and the portion 11 are adapted to be held immovable with respect to each other, so that a pull exerted on 10 will be transferred to rod 11 when an electromagnet generally designated 20 is energized and are adapted to be in effect disconnected when the electromagnet 20 is de-energized. The apparatus for accomplishing this function is as follows:

40 45 A framework consisting of a case having edge plates 21—22 and side walls 23 and 24, together with a top edge plate 25, is assembled and held together by corner blocks 26, the walls being held to the blocks by suitable screws and bolts. The case thus formed is closed at all sides, except along the bottom, as at 27, and serves as an enclosure and framework in which most of the remaining mechanism is housed. Between the

50 55 lower edges of the face plates 23 and 24 there is mounted a block 28 which is screw threaded at

29 to receive the screw threaded end of rod 10. The block 28 is held in place by suitable cap screws at 30. This connection thus firmly attaches the entire case to the upper end of the rod 10 and hence as the rod 10 is pulled downwardly in the direction of arrow 32, the case which is generally designated 34 is likewise pulled downwardly, and when the rod 10 moves upward opposite to the arrow 32, the case 34 likewise moves upwardly. Normally, there is a spring under or attached to treadle 13 which moves it upwardly and this likewise pushes the rod 10 up.

Within the case there is mounted a toggle composed of a pair of links 35 which act in unison and a pair of links 36 which act in unison. The pair of links 36 are pivoted upon the shaft 37 which is passed through holes 38 in the side plate 23 and hole 39 in the side plate 24. Outside of the side plates the shaft 37 has the reduced diameter as at 40 and 41, and on these reduced ends there are mounted spacing washers and then the connecting links 42 and 43, each of which has a vertical slot therein as at 44 for the link 42 and at 45 for the link 43. The slots 44 and 45 are just slightly larger than the diameters of portions 40 and 41 of the pivot pin 37, and hence the links 42 and 43 are free to slide on the portions 40 and 41, being held thereon by the outside washers 46 and 47 which are in turn held in place by wire ring keys at 48 and 49.

The two toggle links 35, which act in unison, are mounted upon a pin 50 that is provided with reduced portions at 52 and 53. These reduced portions extend through a pair of slots 54 in the plate 23 and 55 in the plate 24, these slots being likewise just slightly larger than the diameter of the two reduced portions 52 and 53 of the pin 50, and accordingly the pin 50 is free to move vertically in the slots 54 and 55 in the side plates. Outside the side plates 23 and 24 there are placed spacing washers as at 56 and 57, and outside these the reduced ends 52 and 53 of the pin 60 extend through holes in the lower ends of the links 42 and 43. Thus, the reduced portion 52 of the pin 50 extends through the hole 58 in the link 42 and is held thereon by means of the washer 60 which is in turn held in place by means of the snap ring key 62. Likewise, outside the washer 57 the reduced end 53 of the pin 50 extends through the hole 59 in the lower end of link 43 and is held in place by the washer 61, which is in turn held in place by the snap ring key 63.

The two sets of toggle links 35 and 36 are attached together by means of a toggle pin at 66, which extend not only through the toggle links but also through a pair of supporting plates 67 and 68. The plates 67 and 68 are held spaced apart by means of a short length of tubing as at 69 and the pin 66 thus passes through the plates 67 and 68 and thence through the washers at 70 and 71, thence through apertures in the lower ends of the toggle links 63, thence through washers at 72 and 73, thence through apertures in the upper ends of the links 35 and the ends of the pin 66 are held in place by means of snap ring keys at 74 and 75. The spacing plates 67 and 68, which serve to carry the armature 76 of the electromagnetic unit 20, are also attached to the toggle links 36 by means of a pin at 77, there being likewise a spacing tube at 78, spacing washers at 79 and 80 and retaining washers and snap ring keys at 81 and 82. The plates 67 and 68 hence act in concert and move along with the two toggle links 36 which likewise act in concert. If desired, the two links 36 and plates could have

the plates 67 and 68, respectively, formed integrally therewith.

Between the plates there are a plurality of laminations forming the movable armature 76 of the electromagnetic unit 20, these laminations being held in place by a pair of rivets at 83—83. The electromagnetic unit also includes a stationary magnetic core at 85 which is mounted between the side plates 23 and 24 by means of bolts at 86. Upon the central leg 87 of the electromagnetic path there is a winding at 88 which is served by lines 89. Whenever the lines 89 are energized, this energizes the coil 88 and hence the electromagnetic unit 85 attracts the armature 15 76 and holds it in place, providing it is already adjacent the electromagnetic circuit 85. Shading coils are provided at 90—90 to reduce chatter where the winding 88 is energized with alternating current.

20 In addition, there is provided at 91 a spring which is attached by means of rivets 92 to the side plate 23. This spring extends over between the polepieces of the electromagnetic circuit in a position such that when undeflected it is in 25 the dotted line position as shown at 94. It is in a position to be engaged by the central area 95 of the armature 76 when the latter is adjacent the magnetic circuit 85, and when the magnetic circuit is energized, the armature 76 pulls against 30 the polepieces and depresses the spring 91 to the position shown in full lines at 96. The spring serves to kick the armature 76 away from the polepieces when the magnetic unit 20 is de-energized and hence throws the toggle out of a 35 straight line position, thus initiating motion in a direction to break or fold the toggle.

The upper portion of the slide links 42 and 43 are attached together by means of the bridging block 98 which is held to the links by means of cap 40 screws 99—99. The bridging block is threaded at 97 to receive the lower end of the pull rod 11.

The operation of the device is as follows: In normal operation the two links 10 and 11 when not under any operative pulling force are in the 45 position as shown in the full lines, and circuit 89 is energized. Under such conditions the toggle links 35—35 and 36—36 are in the full line position of Figure 1, which brings the armature 76 into contact with the polepieces of the magnetic circuit 85 of the unit 20, with force sufficient to compress the spring 91 from the dotted line to the full line position. If in this condition the treadle 13 is depressed, force is transmitted to rod 11. Thus, in this position the magnet 20 firmly retains the armature 76 and if then a 55 pull is asserted on rod 10, the toggle in the straight position and held magnetically is not broken to the dotted line position, and hence the force of the rod 10 is transmitted through the side plates 23 and 24 to the upper toggle pin 37, and thence down through the links 36—36, pin 69 and toggle links 35—35 to the pin 50, and hence has a pulling force through the side links 42 and 43 to the connector 98 and hence to the 60 rod 11. Accordingly, when the magnetic device 20 is energized and a pull is placed upon the rod 10, it is transmitted through the entire device 1. the rod 11, and the two rods 10 and 11 are, therefore, effectively coupled together so as to perform their controlling function.

However, if circuit 89 should be de-energized, as might occur when one of the safety devices controlling the press became actuated, and if under the same conditions, with the circuit 89 thus 75 de-energized, the operator pushed on treadle 13

and hence pulls down on the rod 10, this would cause the entire case 34 to move downwardly, or relatively speaking, the rod 11 would pull upwardly, and in so doing causes the slide links 42 and 43 to move from the full line position to the dotted line position. When this occurs, pivot pin 50 attached to the toggle is raised in the slots 54—55 and causes the toggle links 35 to be lifted to the dotted line position of Figure 1, likewise causing the toggle links 36 to be moved to the dotted line position, which also carries the armature 76 to the dotted line position well away from the magnetic circuit of the device 20. Accordingly, when the magnetic device 20 is not energized, a pulling force in the direction of arrow 32 on rod 10 and while rod 11 remains stationary causes the toggle links to be broken to the dotted line position, and hence the pulling force on the rod is not transmitted from rod 10 to rod 11 and hence any mechanism controlled thereby is not in effect operated.

In the form of invention illustrated in Figure 4 the operator-actuated member of the controlling device is in the form of a lever 100 pivoted at 101 so that it can be moved by the operator when force is applied in the direction of arrow 102 on the treadle portion 103. The lever 100 has an upstanding portion at 104 extending over at 105 and provided with a pivot at 106. The cooperating portion of the controlling mechanism (which for controlling action is moved by the foot treadle or lever 100) is shown at 107 and is likewise in the form of a lever pivoted at 108. The lever 107 has a portion 109 extending downwardly and thence towards the portion 104 at the bent portion 110, the latter having a pivot at 111. The lever 107 serves to perform the controlling function which may be by virtue of rotation of pivot 108 or can, if desired, be accomplished by means of a pull rod at 114 which is pivotally attached to the lever 107 by means of the pivot 115.

If the mechanism of which the controlling apparatus forms a part does not inherently include a stop for the motion of lever 107 (or pull rod 114 where used) a stop is provided at 113. Likewise, if the mechanism of the apparatus to which the controlling device is attached, does not normally exert a force in the direction of arrow 116 on lever 107, the spring 117, which is attached to the frame 118, is hooked onto the lever 107 so as normally to hold it in the position shown in Figure 4.

To the pivots 106 and 111 there is attached the free end of a toggle generally designated 120 composed of the link 121 and the link 122, these links being pivoted together at the common pivot 123. An armature 124 is attached to one or the other of the levers 121 or 122 and is positioned so as to cooperate with the polepieces 126 of the electromagnetic device 127 which is served by the circuit composed of the wires 128.

When the wires 128 are energized the electromagnetic device 127 attracts the armature 124 to it solidly, thus holding the toggle 121—122 in the nearly straight condition. Accordingly, if under such conditions the operator presses a foot on treadle 103 the pivot 106 is moved downwardly in the direction of arrow 130 and in so doing imposes a force upon the toggle 120 which therefore exerts a force in the direction of arrow 131 upon the pivot 111, thus causing the portion 110 of lever 107 to be pushed downwardly to effect the controlling operation. A small spring 134 may be provided between the portion 109 of the lever 107 and the toggle 120 so as to urge it normally

towards the broken position shown in dotted lines of Figure 4. However, the spring 134 is very light and is capable of being overcome by the force exerted by the electromagnet 127 upon the armature 124. The spring 134 assists in opening the toggle 120.

In the event circuit 128 is not energized, electromagnet 127, therefore, does not exert force on the armature 124. Accordingly, if under such conditions the operator exerts force in the direction of arrow 102 upon the treadle 103, the force downwardly at pivot 106 cannot be transmitted by the toggle 120 and it accordingly assumes the position shown in dotted lines in Figure 4. It will be appreciated that under the conditions just described, the lever 107 is not moved.

As many apparently widely different embodiments of this invention may be made without departing from the spirit and scope thereof, it is to be understood that we do not limit ourselves to the specific embodiments herein.

What we claim is:

1. In a controller mechanism, a movable operator actuated device having a normal position and having a first pivot thereon, a movable control member having a normal position and having a second pivot thereon adapted to be moved by said device, said first pivot being movable as a part of said device toward the second pivot when said device is operator actuated from its normal position for controlling movement, a toggle composed of a pair of link means, pivoted together by common pivot means, each link means having a free end, said free ends being pivoted on the first and second pivot, said toggle being in a nearly straight condition when the device and member are in their normal positions and movable from said position to a broken position when the device is moved in control effecting direction and said member is not moved, a stop for holding said toggle from assuming an over-center position when the device and member are in their normal positions, and electromagnetic means having an electric circuit connected thereto connected to said toggle for holding said toggle in a substantially straight force transmitting position when the circuit is energized.

2. The apparatus of claim 1 further characterized in that means is provided for biasing said device in a direction opposite to the direction it is moved for effecting control for straightening the toggle.

3. The apparatus of claim 1 further characterized in that bias means is provided for urging said toggle slightly towards broken position, the force of said bias means being so small that it is capable of being overcome by the holding effect of the electromagnetic means when the latter is energized.

4. A device for effectively connecting and disconnecting a force imparting member and a member adapted to be moved thereby in a mechanical control, said members being positioned so as to present a space therebetween comprising a toggle composed of first and second links each having a free end and a common end, said common ends of said links being pivoted together for movement to and from approximately straight and broken positions, said toggle when in approximately straight condition extending across said space between said members with the free end of said first toggle link nearest the force-imparting member and the free end of said second toggle link nearest the moved member, first pivot means connecting the free end of the first toggle link

to the force imparting member and second pivot means connecting the free end of the second toggle link to the moved member, the axes of said first and second pivot means being restrained to movement in substantially the same plane, and electromagnetic means including an electric circuit for maintaining said toggle in said approximately straight condition when said circuit is energized for transferring force therethrough.

5. The apparatus of claim 4 further characterized in that spaced plates having parallel slots therein are provided for maintaining the first and second pivot means in substantially the same plane of movement.

6. An actuator having a bifurcated end composed of spaced portions, a first pivot extending across said portions, a member having a bifurcated end composed of spaced parts having a second pivot thereon, said pivots being held relative to each other so as to be movable in substantially a common plane, with the first pivot between said member and second pivot and said second pivot between said actuator and first pivot, said pivots being substantially parallel, a toggle composed of first and second links pivoted together at a common pivot, each link having a free end, said free ends being pivoted on the first and second pivots, and an electromagnetic device having a controlling circuit attached to said toggle for maintaining it in a substantially straight condition when the circuit is energized.

7. The apparatus of claim 6 further characterized in that said first pivot extends into slots in said parts and said second pivot extends into slots in said portions.

8. The apparatus of claim 6 further characterized in that said parts are in the form of plates substantially enclosing the toggle, pivots and electromagnetic means.

9. The apparatus of claim 4 further characterized in that the force-imparting member is a first lever having a portion to which said pivot means is attached and said member adapted to be moved is a second lever to which said second pivot is attached, and said electromagnetic means is mounted on one of said levers in a position such that when the electromagnet is energized it will hold the toggle in said approximately straight position.

10. In a controller mechanism comprising a manually operable lever having a substantially vertical portion and a portion extending therefrom so as to form a mounting for a first pivot, a toggle comprising a pair of links pivotally connected together with the free upper end of one of said links connected to said first pivot, an actuated member comprising a horizontal lever pivoted at one end thereof, said actuated member having a portion forming a second pivot means to which the lower free end of the other link of said toggle is connected, electromagnetic means mounted upon one of said levers in a position such that when energized it will attract and maintain said toggle in an almost straight line position.
